A. G. F. KUROWSKI.
TYPEWRITING MACHINE.
FILED MAR. 14, 1921.

UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed March 14, 1921. Serial No. 452,359.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

The present invention relates to case-shift- 10 ing mechanism, and is shown applied to an Underwood standard portable typewriter.

In machines of this type, a shift-frame carrying the platen is adapted to be shifted to two raised positions by shift-key levers, 15 one of which is provided with a "Capital" finger-key, and the other with a "Figure" finger-key. The shift-frame is connected to a rock-shaft, to which is fixed an operating arm engageable by the shift-key-levers.

20 Hitherto, in the type of machine herein described, the point of engagement of the shift-key-levers with the operating arm has been a relatively fixed pivot, so that the leverage at the finger-keys remained unchanged 25 throughout the movement of the shift-frame. The inertia of the key-levers and the various parts to be shifted offers a perceptible resistance to being put in motion, and this gives the operator a distinct shock, making 30 the action of the key-levers hard and unpleasant. Moreover, after having been once set in motion, the key-levers move more easily, and there is nothing to absorb the momentum of the operator's finger, as a result 35 of which the shift-frame is brought up against the usual stops with a severe blow.

The present invention has for its object 40 the provision of means whereby the initial inertia of the part to be moved may be overcome and the momentum of the operator's finger absorbed to a large extent before the shift-frame reaches its limiting position. In this way, an easy, pleasant operation of the shift-keys may be obtained. The means 45 employed comprises the substitution of a variable point of pivotal connection between the key-levers and the operating arm, so that the total leverage applied to raising the frame will constantly vary, the greatest 50 leverage being applied in the beginning to overcome the inertia of the movable parts, and the leverage gradually diminishing to absorb the momentum of the operator's finger as the frame reaches its limiting position. 55

Other features and advantages will hereinafter appear.

In the accompanying drawings,

Figure 1 is a side view, vertically sectioned, showing an Underwood standard 60 portable machine as modified by this invention, the shift-frame being in lowermost position.

Figure 2 is a view similar to Figure 1, showing the "Capital" key depressed to 65 raise the shift-frame to its first shifted position.

Figure 3 is a view similar to Figures 1 and 2, showing the "Figure" key depressed to raise the shift-frame to its second shifted 70 position.

Figure 4 is a plan view of one end of the machine, containing the parts shown in Figures 1-3.

In the machine illustrated, character keys 75 (not shown) are adapted to throw type-bars 10 upwardly and rearwardly against the front side of a platen 11, which is journaled in a sheet-metal carriage 12. The carriage 80 travels to the left under control of escape- 85 ment mechanism (not shown), and is provided with roller-bearings 13 and 14, by which it travels on sheet-metal tracks 15 and 16. The tracks 15 and 16 form part of a shift-frame, which also includes a down- 90 wardly-extending member 17 and forwardly- 95 extending members 18, the latter being provided with pivot-screws 19, by which the shift-frame is pivoted to upper long links 21, said links being in turn pivoted to the main frame 22 by pivots 23 nearly behind, but somewhat below, the normal position of pivots 19.

For guiding the shift-frame, there is provided a rock-arm 24 provided with a stub-shaft or pin 25, on which rests a yoke 26 of the shift-frame, said arm 24 being fast at its rear end to a transversely-extending shaft 27, which is encircled by a spring (not shown), so tensioned as to assist in lifting 100 the shift-frame. In order to raise the shift-frame symmetrically, an arm 24 is fixed to shaft 27 at each end of the machine.

For lifting the shift-frame, there is provided a "Capital," or single, shift-key 29, 105 and a "Figure," or double, shift-key 30, fulcrumed on the opposite ends of a short shaft 31, which passes through a standard 32 fixed to the frame of the typewriter. The shaft is headed at one end outside of key 30, and 110

is held by a nut 20 threaded on the opposite end thereof, said nut forming a head outside of key 30. The shift-key 29 is provided with a rearward extension 33, and the shift-key 30 is provided with a rearward extension 34.

The rearward extensions 33 and 34 are adapted to contact with an arcuate surface 37 forming the end of an operating rock-arm 38 fixed to shaft 27. It will be seen that by depressing either key 29 or 30, rearward extension 33 or 34 will raise arm 38 to rotate shaft 27, and hence arms 24, upwardly. Pins 25 on arms 24 will raise the shift-frame.

By depressing the "Capital" key 29, the shift-frame is lifted until an inwardly-turned heel 40 thereon strikes a set-screw 41 passing through the turned-over end 42 of an arm 43, thus enabling the second set 20 of types 44 to print against the platen. By depressing key 30, the shift-frame is lifted a greater distance until a turned-over end 50 of the shift-frame strikes against a set-screw 51 passing through the 25 turned-over end 52 of a bracket 53 fixed to the frame of the machine. To permit the greater movement of the shift-frame when key 30 is depressed, means are provided for swinging set-screw 41 out of the 30 path of the inwardly-turned heel 40. Said means consists in pivoting arms 43 near their lower ends on the machine at 60. The arms 43 form the turned-up portions of a bail 61, to which is connected a spring 62, 35 which normally swings the arms 43, so that the set-screws 41 will be effective to arrest the shift-frame. The bail 61 has fast thereto an upwardly-extending bracket 63, having a rearwardly-extending portion 64 adapted 40 to lie normally on a shelf 65 struck up from extension 34. When key 30 is depressed, extension 34 swings bracket 63 rearwardly, thus rapidly moving set-screw 41 out of the path of heel 40. The platen is 45 thus raised to the second shifted position, enabling types 44 to print thereon.

To produce an easy movement of the shift-frame, which will be agreeable to the touch of the operator, the rearward extensions 33 and 34 terminate at their ends in curved or cam-portions 35 and 36, said cam-portions being adapted to contact with the arcuate surface 37 forming the end of operating arm 38. It will be apparent, from the illustrations (see Figures 1, 2 and 3), that when key 29 or 30 is depressed, the cam-portion 35 or 36 will ride on arcuate surface 37, the point of contact moving rearwardly, i. e., the length of the rear arm of the key-lever constantly increasing until the shift-frame reaches its limiting position. Since the length of the forward arm of each key-lever remains constant, it will be seen that the ratio of the forward arm to the rearward arm decreases as the shift-

frame is raised. In other words, the maximum leverage exists at the finger-key at the beginning of the stroke, said leverage gradually diminishing as the effective length of rearward arm increases. Moreover, the point at which the leverage of the key-levers is applied to the operating arm moves rearwardly of said arm as the shift-frame is raised, thus decreasing the effective length of the operating arm and increasing the resisting force of the shift-frame. It will thus be seen that the greatest key-lever leverage is applied to the greatest effective length of operating arm at the beginning of a stroke. This arrangement 75 renders it comparatively easy to overcome the inertia of the key-levers, and thus avoids the initial shock to the operator's finger. It will be further noted that the leverage at the key-lever decreases as the shift-frame is raised, and that the effective length of operating arm also decreases simultaneously. The resistance offered by the frame to being lifted increases correspondingly, and the momentum of the operator's finger is thus absorbed to a large extent before the shift-frame reaches its limiting position, in this manner easing the shock of the frame as it strikes the limiting stops. 90

It will be understood by reference to the drawing that the curved or cam portions 35 and 36 of the extensions 33 and 34 of the key-levers increase very considerably in curvature adjacent to their tip ends, so that, as the shift-frame approaches the limiting stop 41 under the action of the key-lever 29 or the stop 51 under the action of the key-lever 30, the section of the cam portion 35 or 36, respectively, which engages the arcuate surface 37 of the rock-arm 38, diverges at a much greater degree from the arcuate surface 37 than when the shift-frame is in a lower position. Consequently, as the shift-frame approaches one of its limiting positions, the speed of movement of the rock-arm 38 and the shift-frame is reduced relatively to the speed of movement of the key-levers. In other words, in such position of the shift-frame, an equal movement of the key-lever produces much less movement of the shift-frame than when the shift-frame is in a lower position. This reduction in the speed of movement of the shift-frame lessens the force of the impact of the frame on the stops 41 and 51, and hence reduces the jar and vibration incident to the impact of the shift-frame on the stops. 110

By reference to Figure 1 of the drawing, it will be noted that in the normal positions of the shift-key-levers 29 and 30, that is, with the shift-frame down, the surface of the end portion 35 of the key-lever 29, which engages the arcuate surface 37 of the rock-arm 38, is curved rearwardly away 125

from the arcuate surface 37 of the rock-arm more sharply than is the corresponding surface of the end portion 36 of the shift-key-lever 30. By reason of this construction, the end portion 36 of the key-lever 30, upon operation of the lever, is caused to roll rearwardly on the arcuate surface 37 of the rock-arm 38 to a greater extent than is the end portion 35 of the key-lever 29, so that the shift-key-lever 30 effects a greater decrease in its leverage upon the rock-arm 38 than is effected by the shift-key-lever 29.

Variations may be resorted to within the scope of the invention, and portions of the improvements may be used without others.

Having thus described my invention, I claim:

1. In a typewriting machine, in combination, a shiftable frame, guide-links each pivoted at one end to said machine and at the other end to said frame, a rock-shaft, rock-arms at each end of said frame, each of said arms being fixed at one end to said shaft and supporting said frame at the other end to shift said frame when said shaft is rotated, an additional rock-arm fixed to said shaft and having an arcuate surface lengthwise thereof forming a fulcrum surface, and a shift-key-lever for actuating said additional arm to rotate said shaft, one end of said key-lever contacting with said arcuate surface and having a leverage-changing rolling movement thereon.

2. In a typewriting machine, in combination, a shiftable frame, guide-links each pivoted at one end to said machine and at the other end to said frame, a rock-shaft, rock-arms at each end of said frame, each of said arms being fixed at one end to said shaft and supporting said frame at the other end to shift said frame when said shaft is rotated, an additional rock-arm fixed to said shaft and having an arcuate surface lengthwise thereof forming a fulcrum surface, and a shift-key-lever for actuating said additional arm to rotate said shaft, one end of said key-lever contacting with said arcuate surface and having a leverage-changing rolling movement thereon, so that the leverage upon the shift-frame is greatest at the beginning of a key-stroke and gradually diminishes.

3. In a typewriting machine, in combination, a shiftable frame, guide-links each pivoted at one end to said machine and at the other end to said frame, a rock-shaft, rock-arms at each end of said frame, each of said arms being fixed at one end to said shaft and supporting said frame at the other end to shift said frame when said shaft is rotated, an additional rock-arm fixed to said shaft and having an arcuate surface lengthwise thereof forming a fulcrum surface, and a shift-key-lever for

actuating said additional arm to rotate said shaft, said key-lever being of the first class and having a forward arm and a rearward arm, the end of said rearward arm contacting with said arcuate surface and having a leverage-changing rolling movement thereon during operation of the key-lever.

4. In a typewriting machine, in combination, a frame shiftable to either of two positions, guide-links each pivoted at one end to said machine and at the other end to said frame, a rock-shaft, rock-arms at each end of said frame, each of said arms being fixed at one end to said shaft and supporting said frame at the other end to shift said frame when said shaft is rotated, an additional rock-arm fixed to said shaft and having an arcuate surface extending lengthwise thereof and forming a fulcrum surface, a shift-key-lever for engagement with said fulcrum surface to actuate said additional arm to raise the shift-frame to its first shifted position, said fulcrum surface being of considerably greater width than the contacting surface of said shift-key-lever, a second shift-key-lever also arranged for engagement with said fulcrum surface to actuate said additional arm to raise said frame to its second shifted position, and stops for limiting the upward movement of said frame in each of said positions, said key-levers having a leverage-changing rolling movement on said arcuate surface during operation of the key-levers.

5. In a typewriting machine, in combination, a frame shiftable to either of two positions, guide-links each pivoted at one end to said machine and at the other end to said frame, a rock-shaft, rock-arms at each end of said frame, each of said arms being fixed at one end to said shaft and supporting said frame at the other end to shift said frame when said shaft is rotated, an additional rock-arm fixed to said shaft and having an arcuate surface lengthwise thereof forming a fulcrum surface, a shift-key-lever for actuating said additional arm to raise the shift-frame to its first shifted position, a second shift-key-lever for actuating said additional arm to raise said frame to its second shifted position, and stops for limiting the upward movement of said frame in each of said positions, said key-levers being of the first class and each having a forward arm and a rearward arm, the ends of said rearward arms contacting with said arcuate surface and having leverage-changing rolling movements thereon during operation of the key-levers.

6. In a typewriting machine, in combination, a shiftable frame, guide-links each pivoted at one end to said machine and at the other end to said frame, a rock-shaft, rock-arms at each end of said frame, each of said arms being fixed at one end to said shaft and

supporting said frame at the other end to shift said frame when said shaft is rotated, an additional rock-arm fixed to said shaft and having an arcuate surface lengthwise thereof forming a fulcrum surface, a stop for limiting the movement of the shiftable frame, and a shift-key-lever for actuating said additional arm, said lever being of the first class and having a forward arm and 10 a rearward arm, said rearward arm being provided with an end portion formed to present a curved surface contacting with said arcuate surface and having a leverage-changing rolling movement thereon during 15 operation of the key-lever, the curved surface of said end portion increasing in curvature towards its tip and being arranged to bring a section of increased curvature into contact with the arcuate surface of the rock- 20 arm as the shiftable frame approaches its limiting position, so as to reduce the speed of movement of the frame as it approaches the limiting position and thereby decrease the jar and vibration incident upon the impact of the shiftable frame upon the stop.

7. In a typewriting machine, in combination, a frame shiftable to either of two positions, guide-links each pivoted at one end to said machine and at the other end to 30 said frame, a rock-shaft, rock-arms at each end of said frame, each of said arms being fixed at one end to said shaft and supporting said frame at the other end to shift said frame when said shaft is rotated, an additional rock-arm fixed to said shaft and 35 having an arcuate surface lengthwise thereof forming a fulcrum surface, a shift-key-lever for actuating said additional arm to raise the shift-frame to its first shifted position, a second shift-key-lever for actuating said additional arm to raise said frame to 40 its second shifted position, and stops for limiting the upward movement of said frame in each of said positions, said key-levers being of the first class and each having a forward arm and a rearward arm, the ends of 45 said rearward arms being provided with curved end portions contacting with said arcuate surface and having leverage-changing 50 rolling movements thereon during operation of the key-levers.

8. In a typewriting machine, comprising a shiftable frame, in combination, means connected to said frame whereby said frame 55 may be shifted, said means comprising a forwardly-extending operating arm having an arcuate surface lengthwise thereof, and a shift-key-lever for actuating said arm, one end of said lever contacting with said arcuate surface, said point of contact moving 60 rearwardly on said surface during a stroke of said key-lever to vary the effective length of said operating arm, so that the effective length of said arm is greatest at the beginning 65 of the stroke and gradually diminishes.

9. In a typewriting machine, comprising a shiftable frame, in combination, means connected to said frame whereby said frame may be shifted, said means comprising an operating arm having an arcuate surface lengthwise thereof, and a shift-key-lever for actuating said arm, said lever being of the first class and having a forward arm and a rearward arm, said rearward arm contacting with said operating arm, said point of contact moving rearwardly on said surface during a stroke of said key-lever to vary the effective length of said operating arm, so that the effective length of said operating arm is greatest at the beginning of the key-stroke and gradually diminishes.

10. In a typewriting machine, comprising a shiftable frame, in combination, means connected to said frame whereby said frame may be shifted, said means comprising an operating arm having an arcuate surface lengthwise thereof, and a plurality of shift-key-levers for actuating said arm through different distances, said arcuate surface extending laterally across the path of movement of all of the key-levers and said key-levers being operable in contact with said arcuate surface, the point of contact between each of the key-levers and said surface moving rearwardly on said surface during a stroke of the lever to vary the effective length of said operating arm, so that the effective length of said operating arm is greatest at the beginning of the key-stroke and gradually diminishes.

11. In a typewriting machine, comprising a shiftable frame, in combination, means connected to said frame whereby said frame may be shifted, said means comprising an operating arm having an arcuate surface lengthwise thereof, and a shift-key-lever for actuating said arm, said lever being of the first class and having a forward arm and a rearward arm, said rearward arm having a curved end portion contacting with said arcuate surface and rolling thereon during operation of the key-lever to vary the point of contact to correspondingly vary the leverage of said key-lever and the effective length of said operating arm, so that the leverage of said key-lever and the effective length of said operating arm are greatest at the beginning of the key-stroke and gradually diminish.

12. In a typewriting machine, comprising a shiftable frame, in combination, means connected to said frame whereby said frame may be shifted, said means comprising an operating arm and a plurality of shift-key-levers for actuating said arm through different distances, said arm being formed to present a surface elongated lengthwise of the arm and extending laterally across the path of movement of both of the key-levers, and said key-levers being operable in con-

tact with said surface and being so constructed and arranged with respect to said surface that the point of contact between each of the key-levers and said surface 5 moves on said surface during a stroke of the lever to vary the effective length of the operating arm, so that the effective length of said operating arm is greatest at the beginning of the key-stroke and gradually 10 diminishes.

13. A typewriter case-shift mechanism comprising a shiftable frame, a rock-arm connected to the frame, a plurality of key-levers having arms shaped to roll along said 15 rock-arm, said key-levers being disposed side by side and said rock-arm having a broadened tread to co-operate with said rolling arms, a stop for arresting said shiftable frame, and a connection from one of said 20 levers to withdraw said stop.

14. A typewriter case-shift mechanism comprising a shiftable frame, a rock-arm connected to the frame, and a plurality of key-levers having arms shaped to roll along said rock-arm, said key-levers being disposed side by side and said rock-arm having a broadened tread to co-operate with said rolling arms, said levers being connected to move said shiftable frame through different 25 distances, and the lever that is connected to shift it the greater distance being at its rolling portion shaped to effect a greater decrease in its leverage upon said rock-arm than is effected by the other of said levers. 30
